UNITED STATES PATENT OFFICE

165,229

RIBBON DISPENSER

Joseph M. Katz, Pittsburgh, Pa., assignor to The PaperCraft Corporation, a corporation of Pennsylvania

Application August 16, 1951, Serial No. 16,301

Term of patent 7 years

(Cl. D74—1)

To all whom it may concern:

Be it known that I, Joseph M. Katz, a citizen of the United States of America, residing at Pittsburgh, in the county of Allegheny, State of Pennsylvania, have invented a new, original, and ornamental Design for a Ribbon Dispenser, of which the following is a specification, reference being had to the accompanying drawing, forming a part thereof.

Figure 1 is a perspective view of a ribbon dispenser, showing my new design, the opposite side presenting substantially the same appearance as the side shown, and Fig. 2 is an edge view thereof.

I claim:

The ornamental design for a ribbon dispenser, as shown and described.

JOSEPH M. KATZ.
